UNITED STATES PATENT OFFICE.

GEORGE A. STAFFORD, OF SOUR LAKE, TEXAS.

COMBINATION POWER AND JACK.

Application filed April 14, 1921. Serial No. 461,399.

To all whom it may concern:

Be it known that I, GEORGE A. STAFFORD, a citizen of the United States, residing at Sour Lake, in the county of Hardin and 5 State of Texas, have invented certain new and useful Improvements in a Combination Power and Jack, of which the following is a specification.

This invention relates to new and useful 10 improvements in a combination power and jack.

One object of the invention is to provide a device of the character described specially adapted for use in pumping wells and may 15 be connected to a number of wells and will operate them all at the same time.

Another object is to provide a pump jack, and operating means therefor, whereby the 20 jack may be operated much faster than is the case with similar apparatus now in use, and without any appreciable increase in power.

Another feature resides in an improved 25 form of jack by means of which the leverage is automatically varied as the load varies, greater leverage being available when the load is heavy than when it is light.

A further feature resides in the provision 30 of a jack the length of whose stroke may be readily varied.

With the above and other objects in view 35 this invention has particular relation to certain novel features of construction, operation and arrangement of parts, an example of which is given in this specification and illustrated in the accompanying drawings, wherein:—

Figure 1 is a plan view of the device.

Figure 2 is a side view, and

40 Figure 3 is a transverse sectional view of an eccentric employed.

Referring now more particularly to the drawings, the numeral 1 refers to the derrick floor, the numeral 2 is the well casing 45 and the numeral 3 designates the outlet pipe leading from the well. Fixed to the derrick floor at one side, there is a standard 4, to the top of which the walking beam 5 is pivoted at one end. Attached to the other 50 end of this beam there is a rod clamp 6 provided for attachment to the pump rod 7. A V-bar is pivoted to the derrick floor and is formed with the arms 8 and 10 and interposed between the free end of the arm 8 and 55 the free end of the walking beam there is

the lift bar 9 which is pivotally connected to said arm and beam.

The arm 10 is slotted and its front side has a plurality of transversely aligned bearings 11. The construction above described 60 constitutes the pump jack and connecting parts. The power for operating said jack will now be described.

The numeral 12 designates a stand provided with vertically aligned bearings 65 wherein the shaft 13 rotates. The upper end of this shaft carries a power wheel 14 which is driven by the belt 15. Fixed on the shaft 13 are the oppositely disposed eccentrics 16, 16 surrounding which there are 70 the eccentric yokes 17, 17.

Located between the stand 12 and the jack there is a suitable framework 18, in which the vertical shaft 19 rotates, and fastened to the upper end of this shaft there is a segmental rack 20 which is in mesh with the spur gear 21. This gear is fixed to the vertical shaft 31 and the upper end of this shaft carries a power disc 22. An actuating bar 23 works in suitable bearings carried by 80 the standard 4 and also works through the slot of the arm 10 and its end adjacent said arm is formed with a bearing head 24 which carries bearing lugs 25 disposed to work in the opposing bearings 11. The bar 23 is 85 connected to the disc 22 through the jack line 26 which is connected to the bar by a hook and clevis, as shown. This jack line is usually of considerable length and pivoted eccentrically to said disc. The segmental rack 20 has opposing upturned lugs 27, 27 spaced apart forming bearings for the ends of the adjusting shaft 28. This shaft has reversely threaded sections to receive the nuts 29, 29. The yokes 17 are connected to 90 the nuts 29 through the jack lines 30.

In operation the power wheel 14 is driven by the belt 15 and this operates, through the mechanism described, to oscillate the rack member 20 and rotate the gear 21, and the 100 shaft 31 carrying said gear, back and forth, and through them to also rotate the disc 22 back and forth. The actuating bar 23 is thereby alternately pulled and released through the jack line 26 and the V-bar oscillated back and forth and the walking beam oscillated up and down. On power stroke the pump rod is elevated and when released moves down by gravity.

In practice a number of wells located on 110

different sides of the power and often several hundred yards from it, are connected to, and operated by the power, and they are arranged to balance each other, that is while some are on up stroke and others are on down stroke. This results in a uniform and steady movement of the power and prevents a sudden down stroke of any of the pumps.

10 By turning the rod 28 in one direction the nuts 29 may be run toward each other and the stroke lengthened and in a reverse manner the stroke may be shortened. The stroke may be also adjusted by adjusting 15 the connection of the jack line 26 to the disc 22.

The bearings 11 and 25 have been arranged as shown in Figure 1 for the sake of economy in power. At the beginning 20 of the up stroke, where greatest power is required, the upper bearing of the arm 10 is first brought into play, as shown in dotted lines in Figure 2, thus giving the longest leverage at the time the power disc 25 22 is furthest off center. As the arm 10 moves backwardly the lower bearings 11 and 25 come into play successively, the leverage thus being shortened as the power disc approaches center.

30 The gearing is such that there are two pump strokes for each revolution of the power eccentrics, and the capacity of the jack is thereby relatively increased, resulting in an economy of power.

35 What I claim is:—

1. A device of the character described, including a power wheel, a pair of oppositely disposed eccentrics connected to, and operated thereby, a pump jack, and a mechanism through which said eccentrics are

connected to said jack to operate the same, said mechanism including gearing which imparts two strokes to the jack for each revolution of the power wheel.

2. A device of the character described, including a power wheel, a shaft on which said wheel is fixed, a pair of oppositely disposed eccentrics fixed on the shaft, an oscillating segmental rack, ring-like yokes surrounding said eccentrics, jack lines connecting said yokes with said rack and disposed to oscillate the same as the eccentrics revolve, an oscillating member operatively connected to and actuated by said rack, a pump jack and an operative connection 55 between said oscillating member and jack, whereby the latter is reciprocated from the former.

3. A device of the character described, including a power wheel, a shaft on which said wheel is fixed, a pair of oppositely disposed eccentrics fixed on the shaft, an oscillating segmental rack, ring-like yokes surrounding said eccentrics, jack lines connecting said yokes with said rack and disposed to oscillate the same as the eccentrics revolve, means for adjusting the connection of said jack lines to said rack, an oscillating member operatively connected to and actuated by said rack, a pump jack and an operative connection between said oscillating member and jack, whereby the latter is reciprocated from the former.

In testimony whereof I have signed my name to this specification in the presence 75 of two subscribing witnesses.

GEORGE A. STAFFORD.
